UNITED STATES PATENT OFFICE.

JAMES W. CAMPBELL, OF NEW YORK, N. Y.

ADJUSTABLE WINDOW-CORNICE.

SPECIFICATION forming part of Letters Patent No. 225,339, dated March 9, 1880.

Application filed February 2, 1880.

To all whom it may concern:

Be it known that I, JAMES W. CAMPBELL, of the city of New York, in the county and State of New York, have invented certain new 5 and useful Improvements in Adjustable Window-Cornices, of which the following is a specification.

Various means have been employed to render window-cornices adjustable in length, so 10 as to fit windows of different sizes without cutting. In some cases the two sections of which the cornice is composed are united by a center piece which extends at the front and back sufficiently, in a direction lengthwise of 15 the cornice, to give sufficient strength to the cornice, and in which the two sections may be adjusted toward and from each other.

The object of my invention is to furnish a cornice in which the two adjustable sections 20 or parts are united together so as to slide toward and from each other, and be properly supported and self-sustaining without the aid of the center piece.

To this end my invention consists in a cornice 25 the two adjustable sections of which are each provided at the back with a rigid extension-piece, which overlaps the other section and engages with the other extension-piece in such manner that while either extension-piece 30 is free to slide freely upon the other in adjusting the two sections, each is prevented from moving laterally or vertically relatively to the other. To effect this engagement the extension-pieces are preferably tongued and grooved 35 upon their meeting faces, and each extension-piece carries a gib or bracket engaging with the other extension-piece, for precluding their movement transversely to each other. The center piece is so constructed that it embraces 40 the sections of the cornice and their extensions, and may be adjusted thereon.

In the accompanying drawings, Figure 1 represents a back view of a cornice embodying my invention, showing the same in its contracted position. Fig. 2 represents a similar view, showing the cornice extended; and Fig. 3 represents a cross-section thereof on the dotted line *x x*, Fig. 2.

Similar letters of reference designate corresponding parts in all the figures.

A A' designate the two adjustable sections

of which the cornice is composed, which are exactly similar in shape, and the front of which presents any molding or combination of moldings. Each of said sections has extending from it and rigidly attached to it an extension-piece, the extension-piece B extending from the lower part of the section A, and the extension B' extending from the upper part of the section A', parallel with the 60 extension B. These two extension-pieces are so clamped or secured together, side by side, that while they are free to slip one upon the other in parallel lines they cannot be moved transversely to each other. As here represented, their meeting edges are tongued or grooved, the extension-piece B having a tongue, *a*, and the extension-piece B' having a groove, *b*. By this tongue and groove each of the two adjustable sections A A' is prevented 65 from being moved transversely in a horizontal direction relatively to the other.

In order to prevent movement in a vertical direction and hold the two extension-pieces in tight face-to-face contact, I employ lugs or 70 brackets C, one of which is fixed to the end of each of the two extension-pieces, and is provided with a tongue, *c*, which engages with a groove, *d*, in the edge of the extension-piece.

D designates the center piece of the cornice, the inner surface of which is fitted approximately to the outer face or front of the two adjustable sections, and is held upon the said adjustable sections by a bracket, E, which 75 embraces the back, top, and bottom of the adjustable sections, and is represented as secured to the center piece by screws *e*.

When the cornice is contracted to its shortest length the inner ends of the adjustable 80 sections A A' abut against the bracket E of the center piece, and are precluded from further movement, the center piece being held centrally between them.

When the cornice is extended to its utmost 85 length the stops *f*, which are secured upon the extension-pieces, come in contact with the bracket E of the center-piece, as represented in Fig. 2, and preclude the further extension of the cornice, the center piece being held 90 centrally between the said stops.

When the cornice is adjusted to any inter-

mediate length between its two extreme points the center piece may be readily adjusted along the cornice to a central position.

This cornice may be very quickly adjusted, 5 as all that is required is to slip the two sections together or draw them apart and to adjust the center-piece centrally between or upon them.

By my invention I produce a cornice in which the two adjustable sections are connected independently of the center piece, so 10 as to hold them in their proper relative position and be self-sustaining, and in which the center piece may be adjusted without affecting its strength.

15 What I claim as my invention, and desire to secure by Letters Patent, is—

1. An adjustable window-cornice the two sections of which are each provided with a rigid extension-piece which overlaps the other 20 section and engages with the other extension-piece in such manner that while the extension-pieces are free to slide one upon the other

to effect the adjustment of the cornice they are prevented from moving transversely relatively to each other, substantially as specified. 25

2. The combination, with the two adjustable sections A A', of the two extension-pieces B B', tongued and grooved upon their meeting edges, and a bracket, C, fixed upon each extension-piece and engaging with the other extension-piece by a tongue, e, and groove d, substantially as specified. 30

3. The combination, with the two sections A A', of the extension-pieces B B', the brackets C, for holding them in engagement one 35 with another, the center piece, D, secured upon the cornice by the bracket E, and stops f, for limiting the movement of the sections A A', substantially as specified.

JAMES W. CAMPBELL.
